TANK HANGER

William J. Masoner, Chicago, Ill.

Application October 13, 1947, Serial No. 779,549

1 Claim. (Cl. 248—317)

1

My invention relates to tank hangers and more particularly to an arrangement which fulfills the primary purpose of supporting a tank in any desired position and which may be used to hoist the tank to such position.

While primarily intended for suspending from joists expansion tanks forming part of closed hot water heating systems, the invention is not limited in this respect, but may be used with any tank whose size is such that it is usually supported manually while being installed. Expansion tanks, for example, are customarily supported by metal straps whose ends are nailed or fastened to the floor joists by screws, a common size for home use being thirty gallons and weighing seventy-two pounds, although the size will be larger or smaller depending upon the amount of radiation. This arrangement not only requires at least two men to position the tank, one to support the tank and the other to apply the fastenings, but the fastenings cannot be readily removed when it becomes necessary to replace or repair the tank or remove it to a new location.

It is therefore one object of the invention to provide a tank hanger which is easily and quickly attached to a supporting member and enables the tank to be suspended at any desired distance from the member.

A further object is to provide a hanger of the character indicated which is arranged for quick detachment to permit removal of the tank and which may be utilized to hoist the tank to operative position.

A further object is to devise a method of hoisting a tank to desired position by utilizing the hanger which finally provides the support for the tank.

These and further objects of the invention will be set forth in the following specification, reference being had to the accompanying drawing, and the novel means by which said objects are effectuated will be definitely pointed out in the claim.

In the drawing:

Fig. 1 is an end elevation showing a preliminary step in the hoisting of the tank to final position.

Fig. 2 is a view in reduced scale looking in the direction of the arrow 2 in Fig. 1.

Fig. 3 is a view similar to Fig. 1, but showing the tank in final suspended position.

Fig. 4 is an enlarged elevation of one of the hanger plates, as viewed in Fig. 2, showing the relation thereto of a tank supporting strap and a screw that is threaded in a floor joist.

2

Fig. 5 is a section along the line 5—5 in Fig. 4.

Fig. 6 is a perspective view showing the hanger plate before being conditioned to grip a strap.

Fig. 7 is a perspective view of a swivel block which enables the plate to swing relative to the associated screw.

Referring to Figs. 4 to 7, inclusive, of the drawing, the numeral 10 designates a hanger plate of generally rectangular shape whose upper end, considered with reference to its final position in the assembly, is reversely bent to provide a flange 11 which is spaced from and is parallel to the adjacent portion of the plate and defines therewith a pocket 12. The bight of the bent portion 10 of the plate includes an elongated aperture 13 for a purpose presently explained. The opposite or lower end of the plate may be reduced in width as at 14 and extending normally therefrom on the same side of the plate 10 as the flange 11 is a pair of spaced ears 15—15. Cut through the plate and included wholly within the marginal outline thereof is an opening 16 whose lower boundary is defined by an edge 17 from which centrally extends a tooth 18 that is positioned in the plane of the opening 16. The plate 10 may be originally formed as a stamping and subsequently bent to provide the flange 11 and ears 15.

The hanger pocket 12 is provided to receive a swivel block 19 which may be semi-cylindrical in shape and is transversely apertured at 20 to receive a wood screw 21 which additionally extends through the elongated aperture 13 for attachment to a convenient supporting member, such as a floor joist. The block 19 enables the plate 10 to swing relative to the screw 21 as permitted by the elongated aperture 13. The opening 16 is intended to receive a tank supporting strap 22, preferably made of flexible metal, which includes apertures 23 spaced along the length thereof while the tooth 18 lockingly engages with one of these apertures, all as presently described.

The manner in which a tank 24 is hoisted and held in operative position is more particularly illustrated in Figs. 1 to 5, inclusive, to which reference will now be made. The number of straps employed will generally depend upon the length and weight of the tank, but assuming that two straps are sufficient, two spaced, hanger plates 10 are fastened to a first floor joist 25, for example, by means of screws 21 which are equipped with swivel blocks 19 and, in opposite relation, another pair of hanger plates are similarly attached to the next adjacent joist, as generally indicated in Fig. 1. The plates 10 are

preferably hung so that the ears 15 face away from the tank, thereby rendering them accessible for bending to clamp the strap 22. The locations of the screws 21 may be varied, i. e., they may be threaded in the opposed faces of the joists 25, as actually shown, or in the lower edge faces of the joists. Considerations affecting the placement of the screws, where joists are involved, are the diameter of the tank and the spacing of the joists, as well as the final position of the tank. It will be understood that the joists 25 generally indicate any type of supporting member to which my improved strap hanger may be attached.

Considering the left hand plates 10, as viewed in Fig. 1, one end of a strap 22 is inserted through the opening 16 of one of the plates 10 and bent downwardly to lie between the ears 15-15. This bending is made at a point such that the tooth 18 will project through one of the strap apertures 23, thus providing a locking engagement between the strap 22 and the plate 10. The ears 15 are then bent to overlie and clamp the end of the strap against the plate and thus prevent any tendency of the bent strap portion to straighten when subjected to the weight of the tank. The same procedure is followed with a second strap 22 for the other left hand plate 10.

Both straps are then looped around the underside of the tank 24 which is resting on the cellar floor 26, for example, and the free extremities of the straps are respectively passed through the openings 16 in the right hand plates 10, the several parts occupying the relative positions shown in Fig. 1.

To hoist the tank, it is merely necessary to pull on the free end of one of the straps 22 until one end of the tank is raised a distance such that it will not slip lengthwise along the straps, whereupon the strap just pulled may be temporarily anchored by engaging one of its apertures 23 with the tooth 18 of the associated, right hand plate 10. The free end of the other strap is then pulled to raise the other end of the tank from the floor and possibly above the opposite end of the tank, after which the latter strap may be temporarily anchored in its right hand plate 10 as indicated. Hence, by alternately pulling on the respective straps, the tank is raised to the desired position, the number of separate pulls generally depending upon the distance through which the tank is to be raised. For relatively short distances, one pull on each strap may be sufficient. After the free end of each strap has been anchored by engagement with a tooth 18, the excess part of each strap is cut away and the new extremities are bent downwardly and clamped by bending the ears 15 of the right hand plates 10.

The tank 24 may then be permanently suspended as shown in Fig. 3, or in any selected lower position, either parallel or at any desired angle to the joists 25. An outstanding advantage of this arrangement is its capacity to hoist

the tank in addition to performing its primary function of supporting the tank. With tanks of the size contemplated, one man can hoist and suspend the tank, thus materially reducing labor costs. A further advantage resides in the fact that the tank may be easily taken down by simply bending backward the ears 15 along one side of the tank to unclamp one end of each strap and thereafter disengage the latter ends from the teeth 18.

If the ears 15 fail for any reason, such as where the plate 10 has been used in a number of installations, the strap may be clamped by a bolt and nut (not shown) which is passed through registering apertures 23 in the strap and an aperture 27 in the plate. In installations where it is not possible to use wood screws, such as where the permanent supporting member comparable to the joists 25 is made of metal, the latter may be drilled to receive bolts as substitutes for the wood screws.

I claim:

In tank hanger construction, the combination of a flat plate having laterally extending spaced ears at its lower end and a reversely bent flange at its upper end forming a downwardly opening, curved pocket, the ears and flange extending from the same side of the plate, the flange including an elongated aperture, a swivel block rockable in the pocket and having fastening means extending through the elongated aperture for attaching the plate in depending relation to a support, the plate including an opening therethrough and having a tooth extending into the opening from the lower portion thereof, and a tank carrying, flat strap having a reversely bent end providing opposed portions on opposite sides of the plate and extending downwardly from the tooth, the bent portion of the strap being apertured to receive the tooth for locking engagement therewith, one of the opposed portions being clamped against the plate by the ears.

WILLIAM J. MASONER.
